EDWIN VANDERMINDEN, OF GRANVILLE, NEW YORK, ASSIGNOR TO THE TELESCOPE COT BED COMPANY, OF GRANVILLE, NEW YORK, A CORPORATION OF NEW YORK

CONNECTION FOR COLLAPSIBLE ARTICLES OF FURNITURE

Application filed October 17, 1929. Serial No. 400,205.

This invention relates to connections for articles of furniture and more particularly to pivotal connections for collapsible articles of furniture.

5 An object of the invention is to provide a new, simple, and efficient connection for two members pivotally related in collapsible articles of furniture.

According to the present invention, use is 10 made of a connecting member proper having portions extending at right angles to each other, to one section of which is rigidly secured one member of the article of furniture and to the other of which is pivotally secured 15 another member of the same article of furniture.

In order that these two members may be positioned at right angles to each other and when in this position locked against movement, an arrangement is provided whereby 20 the point of rotation of the movable member is shifted so that the member itself is forced into contact with at least two members spaced apart and lying in substantially the same 25 plane or with a single member of considerable length. When in this position it is impossible to rotate the movable member without shifting its pivotal point away from locking position.

30 Other objects and features of this invention will become apparent by reference to the following detailed description read in the light of the accompanying drawing, wherein:

35 Fig. 1 is a perspective view of one end of a collapsible cot having one embodiment of the present invention therein.

Fig. 2 is a side elevation of one embodiment of the invention showing the parts in 40 their respective positions.

Fig. 3 is an end view of the same device illustrated in Fig. 2.

Fig. 4 is a view somewhat similar to Fig. 2 of a modification of the invention, and

45 Fig. 5 is a view similar to Fig. 3 of the device illustrated in Fig. 4.

Referring now to the drawing, 10 indicates a collapsible cot having legs 11 and 12 supporting one end thereof and connected 50 respectively to side bars 13 and 14 covered

by canvas or other suitable material. Since it is desirable that the cot be collapsed, the connections between the legs 11 and 12 and their respective side bars 13 and 14 are such as to permit pivoted movement of one member relative to the other. 55

In the modification disclosed in Figs. 2 and 3, the connecting member proper is composed of metallic side plates 15 and 16 connected by a plate 17 at one extremity and another plate 18 spaced from the first plate and situated at another extremity of the member. One of the side bars 14 is rigidly secured between portions of the plates 15 and 16, while the leg 11 is pivotally mounted between other 60 portions of these two plates. The pivotal connection for mounting of one member within the connecting device is substantially as follows: In each of the plates 15 and 16 is punched a slot 19 which extends angularly 65 away from the connecting bar 17. The leg 11 is provided with a pin 20 which extends therethrough and also through the two slots 19. Any suitable arrangement is provided 70 for preventing disengagement of the pin 20 from the slots and its leg 11 after the same has been assembled. As will be noted from the drawing, the pin extends through leg 11 some distance from the end thereof, this 75 distance being an amount substantially equal 80 to the distance between the upper extremity of each of the slots 19 and the lower edge of the side bar 14.

If so desired, an angle member 21 may be 85 secured to the side bar 14 when the device is assembled for aiding in supporting the leg 11 when the same is extended at right angles to the bar 14. The free edge 21' of angle member 20 is bent out of alignment somewhat to prevent mutilation of the end of leg 11 which 90 is of wooden construction, while the edge 17' of connecting plate 17 is likewise bent outwardly for the same purpose.

The canvas or other covering material utilized in connection with the device may be 95 subjected to the side bars 13 and 14 in any desired manner and may also be secured to the connecting member for purposes of strength and durability. One type of connection is illustrated clearly in Fig. 3, where- 100

in an eyelet 22 secured in the canvas 23 is clamped in place by means of a tongue 24 punched from the plate 15.

The operation of this connection between 5 the legs represented in this instance by the leg 11 and bar 14 is substantially as follows: Assuming that the article of furniture is in collapsed position with the leg 11 lying substantially parallel to the bar 14, the device 10 may be extended by rotating this leg 11 about its pivotal point. In collapsed position, it will be noted that the end of the leg 11 extends through the space between the plates 17 and 18 and that the pin 20 is positioned in 15 the slot at approximately its upper extremity. The leg 11 may now be rotated about the pin 20 and to permit the end thereof to slide past the upturned extension 17', it is necessary to pull the leg until the pin rests in 20 the lower extremities of slots 19. When it has been completely rotated to extend to right angles with respect to bar 14, the leg 11 may be locked in position by forcing the end thereof directly upwardly into approximate 25 contact with the bar 14. In carrying out this movement, the pivotal point of leg 11 is shifted diagonally so that the outside face 11' thereof rests flush against the inside faces of the plates 17 and 18. In this position as 30 long as any pressure is exerted upon the bar 14 forcing the same downwardly against the end of leg 11, it will be impossible to rotate this leg 11 relative to the bar. The diagonal movement of the pivotal point to bring the 35 face of the leg into contact with the faces of the spaced connecting bars is sufficient to thoroughly lock the leg against movement and for that reason the angle member 21 may be dispensed with, if desired. Until the 40 pivotal point is shifted back to its lowermost position the leg 11 cannot be rotated in either direction. The angle member 21, however, serves other useful functions such as preventing rotation, to any appreciable 45 degree, of the legs in the direction opposite to that desired, which is into the position shown in dotted lines. Attempted rotation in the other direction without member 21 would strain the parts and might possibly 50 result in breakage.

If so desired, the wooden construction of the legs 11 and 12 and the side bars 13 and 14 may be dispensed with and metallic members substituted therefor. This arrangement is illustrated in Figs. 4 and 5 wherein leg 31 is in pivotal relation to a side bar 34. As in the preceding structure, use is made of a connecting member for the leg 31 and bar 34 which is composed primarily 55 of side plates 35 and 36 rigidly secured to the side bar 34 and provided with diagonally extending slots 39 for the passage of a pin 40 extending through the leg 31. Plates 37 and 38 are also utilized for connecting the 60 plates 35 and 36 in a manner corresponding

to the plates 17 and 18. These plates 37 and 38 preferably will be of such shape as to correspond to the configuration of leg 31 and in the present instance they are provided with a curvature corresponding to the periphery 70 of this leg.

The operation and use of the arrangement illustrated in Figs. 4 and 5 is substantially the same as that explained in connection with the preceding structure. Leg 31 may be moved 75 about its pivotal point to lie substantially parallel to bar 34 or may be rotated about its pivotal point to extend at right angles thereto. When so extended, it is locked in position by movement toward the bar 34 which 80 movement shifts its pivotal point diagonally by bringing the outside face of periphery 37 and 38 into contact with the inside faces of plates 37 and 38. In this position it cannot be rotated as long as any forces tend to hold it against 85 movement away from bar 34.

From the foregoing, it will be seen that the present invention provides a connection 90 between two members capable of relative rotation which connection likewise provides for locking these members against rotation when they are at right angles to each other, without the use of a separate locking member as is 95 commonly provided in present collapsible articles of furniture.

While the device constructed in accordance with the present invention has been illustrated as forming a part of a collapsible cot, it will be evident to those skilled in the art 100 that the use of thereof is not restricted to any particular article of furniture, or in fact restricted to articles of furniture. The connection is of material use and advantage in any installation wherein it is desirable to provide a connection between two members having 105 relatively pivotal motion and which are to be locked at right angles to each other for any purpose. It is furthermore to be understood that the present invention is capable of modification and is to be limited only by the scope 110 of the appended claims.

I claim:

1. In an article of folding furniture of the class described, a horizontal frame member, a connecting bracket secured to said member and comprising one side with a cut-out portion, registering slots in the adjacent sides inclined slightly from parallelism with and towards the end of the cut-out side nearer the frame member, said slots substantially within the projected area of said cut-out portion, a supporting bar, pivots at its upper end pivotally and slidably engaging the slots of said bracket, said bar adapted when positioned at right angles to the frame member to be 120 wedged against the cut-out side of the bracket by the action of the inclined slots and the pivots when pushed towards the frame member and to have its end swing through the cut-out portion of the one side for folding 125

when the bar pivots are brought to a lower position in said slots.

2. In an article of the character described, a frame member, a connecting bracket of channel form secured to said member, an opening in the rear of said channel bracket at right angles to the frame member, registering slots in the sides of said bracket substantially in the area between the upper and lower limits of the opening, a supporting leg for said member comprising a set of pivots at the upper end thereof, said pivots engaging in said slots, and adapted when at right angles to the frame member and pushed upwardly in the bracket slots to be wedged against the back of the bracket channel and when withdrawn from such position to fold by virtue of the upper end swinging through the opening in the back of said channel bracket.
- 20 In testimony whereof, I have signed my name to this specification.

EDWIN VANDERMINDEN.
